UNITED STATES PATENT OFFICE.

GEORGE W. MINGLE AND WILLIAM T. BROWN, OF PHILADELPHIA, PENNSYLVANIA, ASSIGNORS TO SAID WILLIAM T. BROWN.

PROTECTOR FOR ELECTRIC WIRES AND INSTRUMENTS.

SPECIFICATION forming part of Letters Patent No. 352,342, dated November 9, 1886.

Application filed April 2, 1886. Serial No. 197,554. (No model.)

To all whom it may concern:

Be it known that we, GEORGE W. MINGLE and WILLIAM T. BROWN, both citizens of the United States, residing in the city and county 5 of Philadelphia, State of Pennsylvania, have invented a new and useful Improvement in Protectors for Electric Wires and Instruments, which improvement is fully set forth in the following specification and accompanying 10 drawings, in which—

Figure 1 represents a side elevation of an electrical protector for wires and instruments embodying our invention. Fig. 2 represents a section thereof in line *x x*, Fig. 3. Fig. 3 15 represents a plan or top view of the same. Fig. 4 represents a transverse section in line *y y*, Fig. 1.

Similar letters of reference indicate corresponding parts in the several figures. 20 Our invention relates to improvements in apparatus for the protection of telegraph, telephone, and other electrical instruments, and the wires, cables, or conductors attached thereto, from the destructive effects of abnormal electric currents.

Referring to the drawings, A represents a base of some suitable insulating material. Placed thereon at one end is a nut, B, having 25 electrical connection with the metallic block C and the lever D through the medium of the shaft E, on which the lever D is free to move. Coiled around the hub of the lever D, and rigidly secured thereto at one end, is the spring F, which engages on its other end with the 30 supporting post on the block C of said lever and tends to turn it on its axis.

G G' represent uprights, one of insulating material and the other metal, having stretched 35 between them the wires H H' H², the uprights G G' being supported on the base A at such distance from the block C that the wires H will engage the end of the lever D.

E' represents a wire electrically connecting the metal upright G to the coil of the electro- 40 magnet J.

On the base A is also placed the electro- 45 magnet J, having the core K and armature L, the coil of said magnet being composed of wire of coarser grade than the fusible wires H H' H², 50 and the said armature being constructed of an

iron piece, L', and a flat spring portion, L², properly secured thereto, the said armature with its spring-piece being so placed that the said spring-piece is adapted to be brought in contact with a post, R, secured to the base A 55 of the device. The spring-piece may be dispensed with and the end of the metallic piece L be directly over the post R. The armature L is suitably pivoted and supported on the upright M, which is insulated from the said 60 upright G, and has an extension, N, engaging the tension-spring P, suitably secured. The tension of the spring P serves to keep the armature L from the electro-magnet J. A binding-post, I, is secured to the said base. The 65 nut B is in electrical connection with the core 70 of the magnet J, and also with the post R.

B' represents the main line of a telegraph or telephonic circuit, which latter may be of any form or make, and, not being claimed by itself, is not shown in the drawings. The ground wire C' is connected to the post R, the core K, and the binding-plate and post S', and from thence is run to the ground. The top wire, D', connects the binding-post S with the base 75 of the armature-support.

The operation is as follows: The lever D is depressed and the fine wires H properly connected. The current of the circuit enters 80 through the block C by means of a clamp, screw, or nut, B, passes through the block C, thence into the lever D through the fine wires H, thence through the piece which supports the upright M into the electro-magnet J, thence to the binding-post S, whence it passes to the 85 instrument. Should an abnormal current cross the line, it will pass through nut B, block C, lever D, fusible wires H H' H², metallic upright G, wire E', coil of electro-magnet J, magnetizing the core thereof and thereby attracting 90 the armature so as to close the circuit with post B, and thence to ground, the circuit also containing wire J', binding-post S, top wire, D', and support of armature, by which means the coil of the magnet is not shunted during 95 passage of the current, but continues in the circuit, and is thereby enabled to continuously magnetize the core, preventing vibrations of the armature. The descent of the armature L at first brings the spring L² in contact with the 100

post R, the ground-wire connection of which runs the current to the ground, by which means the instrument to be protected is removed from the circuit and the current is 5 short-circuited or condensed upon the fine wires H, causing them successively to fuse and separate as the abnormal current may continue, which allows the lever D to rotate, thus entirely breaking the circuit. As the abnormal 10 current passes to the ground and from the coil of the magnet, the coil is no longer magnetized, thus releasing the armature, the ground-connection being thereby broken. The spring L² may be dispensed with and the armature L extended, so as to come directly in contact with the post R. Instead of the circuit being shunted from the magnet J, it may pass through the magnet to avoid vibrations of feeble, though dangerous, currents.

20 Fig. 1 shows the instrument in its normal position, in which the line enters at the nut B, thence by the block C and lever D to the wires H, thence to the upright G, and by wire E' to the coil of the electro-magnet, and thence to 25 the binding-post S and through the instrument.

An abnormal electric current—such as lightning—entering at the block C will fuse one of the fine wires H, in which case the lever D will 30 make contact with the next fine wire H, thus insuring the continuity of the circuit. Should, however, a heavy or continuous abnormal current enter at the post B, the electro-magnet J will be energized, thereby attracting the armature L, which, on making contact with the post R and thence to the ground direct throws full strength of the abnormal current through the wires H, which instantly fuse, releasing the lever D, and thus breaking the circuit.

40 We do not limit ourselves to the form of electro-magnet herein shown, as we can adopt any other in lieu thereof. Instead of fusing strips of wire, we can use strips of fusible metal.

Having thus described our invention, what 45 we claim as new, and desire to secure by Letters Patent, is—

1. In an electric protector for wires and instruments, the combination of an insulating-base having thereon a rotating lever, fusible 50 wires, and an electro-magnet having an armature normally in the electric circuit and adapted to complete the connection with the ground-wire, substantially as and for the purpose set forth.

55 2. An electric protector for wires and instruments, having a rotating lever, fusible wires adapted to be in contact with said lever, an electro-magnet having its coil electrically connected to said fusible wires, an armature 60 electrically connected to said coil and adapted to be brought in contact with the core of said magnet when an abnormal current of electricity is passed through the said circuit, and a ground-wire attached to said core, all of said

parts being combined and arranged substantially as and for the purpose set forth. 65

3. In an electric protector for wires and instruments, a rotating lever, fusible wires adapted to be in contact with said lever, an electro-magnet having its coil electrically connected to said fusible wires and to the instrument to be protected, and means, substantially as described, actuated by the passage of an abnormal current of electricity for grounding said current without shunting the electro-magnet, all combined substantially as described. 70

4. In an electric protector for wires and instruments, a rotating lever, fusible wires, an electro-magnet, a binding-post, wires electrically connecting the coil of said magnet, fusible wires and binding-post, a tap-wire connecting said binding-post and the base of the armature-support, a contact-post having a ground-wire, all of said parts being combined and arranged whereby an abnormal current of electricity may be grounded without passing to the instrument to be protected. 80

5. In an electric protector for wires and instruments, an insulated base, A, having suitably secured thereon a rotary lever, fusible wires on supports G G', the former metallic, the latter insulated, the electro-magnet J, electrically connected to fusible wires and to binding-post S, all of said parts being combined 90 substantially as and for the purpose set forth. 95

6. In an electric protector for wires and instruments, a rotating lever, fusible wires in contact with said lever, an electro-magnet having its coil in electric connection with said wires and a binding-post, the latter having a wire connection with the instrument to be protected, an armature adapted to be brought in contact with the core of said magnet, a ground from said core, and a tap-wire electrically connecting the said binding-post to the base of said armature-support, all of said parts so combined and arranged whereby an abnormal current may be grounded, substantially as and for the purpose set forth. 100 105

7. An electric protector for wires and instruments, having a metallic armature-support with the armature, an electro-magnet having its coil connected to a binding-post, and a wire electrically connecting said binding-post with the base of the armature-support, whereby an abnormal current of electricity passing through said coil, while actuating the armature and grounding the current, continues to magnetize the core of the magnet 115 during the passage of the said abnormal current, substantially as described. 120
